US0D1029949S

(12) **United States Design Patent** (10) **Patent No.:** **US D1,029,949 S**
(45) **Date of Patent:** **** Jun. 4, 2024**

(54) **ELECTRIC SCOOTER**

(71) Applicant: **RAZOR USA LLC**, Cerritos, CA (US)

(72) Inventors: **Joey Chih-Wei Huang**, Temple City, CA (US); **Robert Chen**, San Marino, CA (US)

(73) Assignee: **Razor USA LLC**, Cerritos, CA (US)

(**) Term: **15 Years**

(21) Appl. No.: **29/666,938**

(22) Filed: **Oct. 17, 2018**

Related U.S. Application Data

(63) Continuation of application No. 29/591,292, filed on Jan. 18, 2017, now abandoned.

(51) **LOC (14) Cl.** **21-01**

(57) **CLAIM**

The ornamental design for an electric scooter, as shown and described.

DESCRIPTION

FIG. 1 is a top, rear, left-side perspective view showing an embodiment of an electric scooter embodying our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines are for the purpose of illustrating portions of the article that form no part of the claim.

1 Claim, 6 Drawing Sheets
